UNITED STATES PATENT OFFICE.

ARTHUR E. HOTCHKISS, OF CHESHIRE, CONNECTICUT.

DEVICE FOR MAKING VERGES AND PENDULUM-RODS.

SPECIFICATION forming part of Letters Patent No. 250,072, dated November 29, 1881.

Application filed January 25, 1881. (Model.)

To all whom it may concern:

Be it known that I, ARTHUR E. HOTCHKISS, of Cheshire, in the county of New Haven and State of Connecticut, have invented certain 5 new and useful Improvements in Devices for Making Verges and Pendulum-Rods; and I do hereby declare the following to be a full, clear, and exact description of the invention, such as will enable others skilled in the art to which 10 it pertains to make and use it, reference being had to the accompanying drawings, which form part of this specification.

My invention relates to an improved device 15 for making verges and pendulum-rods, the object being to provide mechanism for securely retaining the pallets, yoke, verge-shaft, and pendulum-wire in proper relative position for securing such parts together; and with this end in view my invention consists in certain 20 details in construction and combinations of parts, as will hereinafter be described, and pointed out in the claims.

In the accompanying drawings, Figure 1 is a 25 view in perspective of my improved device, the parts being in proper position for receiving the different parts of a verge and the pendulum-wire. Fig. 2 is a similar view, showing the different parts of the verge and the pendulum-wire secured in place and ready for being soldered together. Fig. 3 is a transverse 30 section of one of the pallets. Fig. 4 is the pendulum-wire. Fig. 5 is a view in perspective of the combined verge and pendulum-wire, and Fig. 6 is a rear view of my improved device.

A represents the base, and B the standard, the latter being formed with a recess, *a*, in its 35 upper end, within which is located a knife-edge bearing, *b*.

C is the pallet-supporting plate, it being secured to the standard B by means of one or more screws, *c*. Plate C is provided with two notches or recesses, D D', which are located at such distance apart and relative angle to each other as are necessary in the pallets of the 45 verge, in order to insure the desired action on the teeth of the crown or escape wheel of a clock-movement.

E is a lever, pivoted at *d*, said lever being provided with a pointed end, *e*, which is held 50 down over the lower recess or notch, D', by means of the spring F acting against its long arm.

G is a lever, pivoted at *g*, and provided with a sharp pointed end, *g'*, which is held down over the recess D by means of a spring, G'. 55

An upright shaft, H, is attached to or connected with the standard B, the upper end thereof being provided with a knife-edge bearing, *b'*. A lever, I, is pivoted at *i*, and is provided with a bearing-point, *i'*, which may be 60 moved in line with the bearings *b b'*, and the point *i'* be retained in its depressed position by means of the spring *i''*. The lever I may be swung around so as to carry the point *i'* out of line with the bearings *b b'*. To the under side 65 of lever I is secured a pin, J, which engages with a pin, *j*, attached to standard B, and thus limits the movement of the lever in one direction.

K is a flat spring, secured to the standard 70 B by means of a screw, the free end *k* of the spring being out of contact with the standard.

L is a gage-block, having a notch, *l*, formed in one end thereof for the reception of the pendulum-wire. The opposite end of the block 75 L is provided with an elongated slot, *l'*, through which passes a screw, *L'*. By this construction the gage-block may be adjusted lengthwise, and thus readily secured in any desired position.

M is a spring-clamp, pivoted at *m*, and adapted to be swung around over the pendulum-wire to hold it in place. 80

N represents one of the pallets, which is preferably made as follows: Steel wire is rolled to the form of a knife-edge, as illustrated in 85 Fig. 3, and is then hardened and polished and severed into the desired lengths for pallets.

O is the verge-yoke, having two triangular or V-shaped openings formed therein, within which are secured the V-shaped pallets N. A 90 round hole is formed in the yoke for the insertion of one end of the pendulum-wire.

P is the pendulum-wire, one end thereof being provided with a hook, *p*.

Having described the construction and relative arrangement of the different parts of my improved device, I will now describe the method of operating its several parts. 95

The outer ends of levers E and G are depressed, thereby raising their pointed ends 100 from the notches or recesses D D' in the pallet-supporting plate. Pallets N, of the form shown in Fig. 3, are then inserted in the notches or recesses D D' and the outer ends of the levers

released, thereby allowing the lever-springs to cause the points *e* and *g'* to rest upon the backs of the pallets and secure them against displacement. A yoke, *O*, of the form shown, 5 is then placed onto a verge-shaft, *O'*, and the **V**-shaped bearings of the latter seated upon the sharp-pointed bearings *b b'*. Lever *I* is then swung around on its pivot and its point placed on the top of the verge-shaft. The lever 10 being released, the spring connected therewith serves to press the point *i'* against the verge-shaft, and thus prevent any accidental displacement of the latter. The hooked end *p* of the pendulum-wire is inserted in the hole 15 in the yoke *O*, and the latter forced back and the projecting ends of the pallets forced into the **V**-shaped holes or openings formed therein. The lower end of the pendulum-wire is inserted in the notch *l* in the gage-block *L*, 20 and secured therein by means of the pivotal clamp *M*, which is swung around over the pendulum-wire, the latter being prevented from becoming disengaged from the yoke by means of the spring *K*, upon which rests the upper 25 end thereof. The parts having all been secured in position as described, solder is applied to the outer surface of the yoke, and serves to secure the verge-shaft, pallets, pendulum-wire, and yoke together, and all in proper 30 position for being placed on a clock-movement and put into operation without other fitting.

The gage-block *L* may be adjusted so that the pallets and pendulum-wire will sustain such 35 relative position one with the other that when the pendulum is applied the escapement will be practically perfect without other fitting.

This improved device produces a great saving in the manufacture of verges, as it enables 40 the parts to be quickly attached to each other and greatly simplifies the labor and materially reduces their cost; and, further, by its employment the combined verges and pendulums are made uniform in shape and perfect in operation. 45

Instead of employing two levers for retaining the pallets in position in the pallet-supporting plate, one lever may be arranged to effect the same result. In such construction 50 the single lever would be provided with two holding-prongs of such shape that it would fit upon both pallets and retain them in place.

It is evident that many slight changes in the construction of the different parts of the de-

vice might be resorted to without involving a 55 departure from the scope of my invention, and hence I would have it understood that I do not restrict myself to the exact construction and arrangement of parts shown and described; but,

Having fully described my invention, what I claim as new, and desire to secure by Letters Patent, is—

1. The combination, with a pallet-supporting block and levers for retaining the pallets therein, of supports on opposite sides of the pallet-block for supporting the verge-shaft, substantially as set forth. 65

2. The combination, with a pallet-supporting block or plate and devices for retaining the pallets in place, of supports on opposite sides of the pallet-block for supporting the verge-shafts, and a lever adapted to prevent the displacement of the verge-shaft, substantially as set forth. 70

3. The combination, with devices for retaining the pallets and verge-shaft in place, of a device for retaining the pendulum-wire in the verge-yoke until secured thereto by solder, substantially as set forth. 75

4. The combination, with devices for retaining the pallets and verge-shaft in place, of devices for retaining the pendulum-wire in the verge-yoke and devices for securing the lower end of the pendulum-wire in any desired adjustment, substantially as set forth. 85

5. The combination, with devices for securing the pallets and verge-shaft in position, of an adjustable pendulum-wire gage-block, and a clamp for retaining the pendulum-wire in position, substantially as set forth. 90

6. A device for fitting combined pendulum-wire and verge, consisting, essentially, of a pallet-supporting block or plate, spring-pressed lever or levers for securing the pallets in place, 95 a spring-pressed lever for securing the verge-shaft in place, a spring for securing the pendulum-wire in the verge-yoke, and an adjustable gage-block and pivoted spring-clamp for retaining the pendulum-wire in proper adjustment, substantially as set forth. 100

In testimony that I claim the foregoing I have hereunto set my hand this 14th day of September 1880.

ARTHUR E. HOTCHKISS.
